DESIGN FOR A WASTE BASKET OR SIMILAR CONTAINER

Martha H. Connor, Baltimore, Md., assignor to Owens-Illinois Can Company, Wilmington, Del., a corporation of Delaware

Application December 12, 1936, Serial No. 66,502

Term of patent 7 years

To all whom it may concern:

Be it known that I, Martha H. Connor, a citizen of the United States, residing at Baltimore, in the State of Maryland, have invented a new, original, and ornamental Design for a Waste Basket or Similar Container, of which the following is a specification, reference being had to the accompanying drawing, forming a part thereof.

The drawing is a perspective view of a waste basket or similar container showing my new design, the surface decoration illustrated appearing on opposite sides of the article.

I claim:

The ornamental design for a waste basket or similar container substantially as shown and described.

MARTHA H. CONNOR.
